PHOTOGRAPHIC CAMERA WITH PROVISION FOR SIDE MOUNTED STROBE

Cooper C. Woodring, Plandome, and Ronald Emmerling,
New City, N.Y., assignors to J. C. Penney Co., Inc.,
New York, N.Y.

Filed June 26, 1974, Ser. No. 483,393

Term of patent 14 years

Int. Cl. D16—01

U.S. Cl. D16—6

FIG. 1

FIG. 2

FIG. 3

FIG. 4

FIG. 5

FIG. 6

FIG. 7

FIG. 8

FIG. 9

FIG. 10

FIG. 1 is a front perspective view of a photographic camera with provision for side mounted strobe showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side elevational view thereof;

FIG. 7 is a right side elevational view thereof;

FIG. 8 is a front elevational view of FIG. 1, showing an alternate embodiment of the light sensing portion;

FIG. 9 is a front elevational view of FIG. 1 showing a second alternate embodiment of the light sensing portion; and

FIG. 10 is a front elevational view of FIG. 1, showing a third alternate embodiment of the light sensing portion.

We claim:

The ornamental design for a photographic camera with provision for side mounted strobe, substantially as shown and described.
